HAND OPERATED WRAPPING MACHINE

Henry Ernest Goerke, Floral Park, and Gustave Adolph Bystrom and Harry William Schmale, Brooklyn, N. Y., assignors to American Machine & Foundry Company, a corporation of New Jersey

Application May 5, 1934, Serial No. 724,150

20. Claims.

(Cl. 93—2)

This invention relates to hand operated wrapping machines which fold wrappers about articles of irregular shape such as loaves of bread or about packages of rectangular cross-section such as cartons, etc., and seal the wrapper thereabout.

The main object of this invention is the provision of a manually operated machine in which the article to be wrapped is inserted by hand and the wrapper is manually placed in position to be folded about the article. A further object of the invention is the provision of manually operable means for drawing the web of wrapping material from a roll and severing a wrapper blank from the web, consisting of a handle connected through a gear train to a pair of coacting web-feeding rollers and also connected to a web-severing knife so that the web will be drawn off the roll when the handle is depressed and severed when the handle is raised. Another object of the invention is to raise the article into the positioned wrapper, thus enfolding the article therein, and raise the enfolded article between tuckers which tuck the wrapper down over the ends of the article. For this purpose the lifter is connected to a treadle in such a manner that the lifter will be raised when the treadle is depressed by the attendant.

Another object of the invention is to advance the partially wrapped article from the lifter over a heated sealer table, which wipes the skirt of the wrapper under the article and heat seals the bottom seam thus formed as the partially wrapped article is advanced thereover, and between stationary folders which fold in the end flaps of the wrapper then projecting from the article by means of a pusher mounted on a manually movable slide. In order to complete the end folding operation with a single forward movement of the slide the same is provided with spaced end folders which fold the rear end flaps of the wrapper over the top tuckers and carry cams which raise the tuckers up from the partially wrapped article which is then advanced between the stationary folders. During this advance of the partially wrapped article the lifter must be slightly lowered to permit one wrapper end to be folded under its bottom; accordingly, still another object is to provide a device for latching the lifter in an elevated position and mechanism for unlatching the lifter to permit it to drop slightly and then finally return to its lower position. With these and other objects not specifically mentioned in view, the invention consists in certain constructions and combina-

tions hereinafter fully described and then specifically set forth in the claims hereunto appended.

In the accompanying drawings which form a part of this specification and in which like characters of reference indicate the same or like parts:

Fig. 1 is a side elevation of the hand operated wrapping machine;

Fig. 2 is a top view taken on line 2—2 of Fig. 1, showing the arrangement of the folding and sealing members;

Fig. 3 is an enlarged side elevation of the lifter and the lifter release mechanism;

Fig. 4 is an end elevation of Fig. 3;

Fig. 5 is an enlarged side elevation of the web feed and web severing mechanism;

Figs. 6 to 13 are end elevations in enlarged scale, showing the successive steps for folding the wrapper about the article; and

Fig. 14 is a perspective view of a finished package.

In carrying the invention into effect there is provided manually operable means for drawing a web of wrapping material from a roll and severing a wrapper from the web, devices for supporting the severed wrapper in a horizontal position, spaced swingable tuckers above said devices, a lifter arranged to move an article upwardly between the devices and tuckers for draping the wrapper about the article and tucking the wrapper down over the ends of the article, a horizontally movable slide, a bottom folder and a pair of end folders adapted to fold one wrapper end under the article and fold the forward side flaps over the tuckers, respectively, a heated sealer table arranged to wipe the skirt of the wrapper under the bottom of the partially wrapped article when pushed thereover and heat seal the bottom seam so formed, stationary folders on the table for completing the folding of the end flaps, a pusher on the slide for advancing the article onto the table and between the stationary folders, spaced cam rails on the pusher adapted to lift the tuckers up from the article, sealing plates beyond the stationary folders to heat seal the end flaps, and cooling plates beyond the sealing plates. In the best constructions contemplated there is provided a treadle for raising the lifter, a latch for retaining the lifter in an elevated position, and means controlled by a cam on the slide for disengaging the latch from the lifter. The web-feeding and severing means in the best constructions includes a pair of coacting feed rollers operative to draw the web from the roll and feed it into position to

be severed, a gear train for driving the rollers, a stationary ledger plate, a movable knife opposite the ledger plate, and a handle connected to the gear train and knife so that when the handle is depressed the web is fed by the rollers and when the handle is raised the web is severed by the knife. These various means and parts may be widely varied in construction for the particular machine selected to illustrate the invention. 5.0 is but one of many possible concrete embodiments. The invention, therefore, is not to be restricted to the specific construction shown and described.

Referring to Figs. 1 and 2 of the drawings, the 15 side frames 20 and 21 are held together by tie frames 22 and 23, and tie bars 24 and 25. To the top of side frame 20 is secured a bracket 26 and to the other side frame 21 in a like manner is secured a bracket 27. The brackets 26 and 27 20 carry pusher slide bars 28 and 29 respectively. Studs 30 set in one end of the slide bars 28 and 29 support the cross bar 31. A pusher bar 32 is slidably mounted on the slide bars 28 and 29 behind the bar 31. A rod 33 attached to the 25 bar 32 passes through an opening in the cross bar 31, the opening being large enough to allow the rod to slide freely therein. A hand-grip 34 fastened to the rod 33 may be grasped by the attendant for actuating the pusher bar 32. A pair of brackets 35 suspended from the 30 studs 30, and clamped against the bar 31 by nuts threaded thereon, support a guide plate 36. A bottom folder 37 which forms the first under-fold of the wrapper about the article, is also 35 mounted on the studs 30, the same being held between the bars 31 and 32. A pusher plate 38 attached to bar 32 advances the articles through 40 their different folding operations. Adjustably mounted on the pusher 38 in spaced relation are a set of channel-shaped clamp plates 39 carrying end folders 40, said folders operating to fold in the forward side flaps of the wrapper as will 45 be presently described. To the clamp plates 39 are secured the angles 41, the adjustably mounted cam rails 42, which when moved inward with the pusher 38 encounter rollers 43, thus raising the same and in so doing lifting the tuckers 44, which fold down the top flaps of the wrapper as 50 hereinafter described. The rollers 43 are mounted on studs supported in lugs 45 suspended from arms 46 which carry the folders 44. The arms 46 are pivotally mounted on studs 47 carried by the frames 48. The ledges 49 of the folders 44 normally rest on the frames 48 when the folders 55 are in their down position.

Referring now to Fig. 2 alone, in which, since the mechanism shown at the right hand portion thereof is the same in construction as that at its left hand portion, with the exception of the 60 adjusting means, like members will carry the same reference numbers.

The upwardly extending arms 50 and 51 of the brackets 26 and 27 each carry a stationary cross bar 52 and a rack 53. The frames 48 are suspended from the members 52 and 53 by means of bolts 54 having wing nuts 55 engaging with the caps 56 disposed between the nuts 55 and the members 52 and 53. The frames 48 carry the folder plates 56a, the front edges of which 65 fold in the projecting side flaps of the wrapper, and the slots 57 therein receive the projecting bottom flaps of the wrapper, thereby 70 gradually folding the same in over the flaps previously folded against the ends of the article. The frames 48 also carry a pair of bent

straps 58 equipped with stud-bolts 59 set in the sealer plates 60. The studs 59 carry springs 61 which are seated between the straps 59 and the sealer plates 60; in this manner the sealer plates are yieldingly mounted so that they may 5 accommodate themselves to any variation in the length of the articles. Each sealer plate 60 is provided with an electric heater 62 which serves to heat the same sufficiently for sealing together the flaps of the wrapper overlapped on the ends 10 of the article. A second pair of straps 63 attached to each of the frames 48 carries the cooling plates 64, the latter being yieldingly mounted in the same manner as the sealers 60.

The side frames 20 and 21 have lugs 65 and 15 66 which support the bottom sealer table 67. The table 67 is equipped with electric heaters 68 which heat the same sufficiently for sealing the bottom seam of the wrapper. The far end of the table 67 has a ledge 69 to which is fastened 20 by a number of thumb screws 70 one end of the cooling table 71, the other end of table 71 resting on a cross bar 72. One end of the delivery table 73 rests on the bar 72, and it is attached to bars 74 which rest on the tie bar 24 and extend transversely thereof. The table 73 is provided with knobs 75 threaded on the stud-bolts 76 which pass through the table 73 and are threaded into the lock members 77 provided with ledges 78 extending under the bar 72. Therefore, when the knobs are tightened on the stud-bolts 76, the table 73 is clamped against the top of bar 72 and the ledges 78 are pressed against the bottom on the bar 72, thus assuring a rigid mounting for the table. 35

All the folding members on the frame 48 shown at the left hand portion of Fig. 2 are set correctly at assembly and need not be moved. To accommodate different lengths of articles, the frame 48 shown at the right hand portion 40 of Fig. 2 is made adjustable. The latter frame 48 carries bearings 48a supporting a shaft 49a, one end of said shaft carrying a hand wheel 50a. A pair of pinions 51a mounted on shaft 49a mesh with the stationary racks 53. To adjust this frame 48 the wing nuts 55 thereof are loosened and then, by turning the hand wheel 50a, the entire frame 48 with the folder members carried thereon may be shifted to the desired position. 50

The tie bar 25 supports a yoke 79 carrying a stud 80 on which is fulcrumed at treadle 81, the other end of the treadle carrying a pad 82. The treadle 81 is guided in a slotted bar 83 suspended from the tie frame 23 and carries a screw 84 to which is secured one end of a cable 85, the other end of cable 85 being fixed in a recess in the periphery of pulley 86. A pulley 87 which is coaxial with the pulley 86 has a recess which is diametrically opposite to the recess in 60 pulley 86. In the recess in the periphery of pulley 83 is held one end of a cable 88, the other end of cable 88 being looped under the head of a screw 89 threaded into the lifter bar 90. 65

Thus, when the treadle 81 is depressed, the pulley 86 is turned by means of the cable 85 and the pulley 87, which may be integral with or fast to pulley 86, is turned with the pulley 86 causing the cable 88 to be wound on the pulley 87 thereby lifting the bar 90. The pulleys 70 86 and 87 are free to revolve on a stud 91 set in the bar 83. The bar 90 also supports a dash pot 92, the bore of pot 92 fitting a stationary piston 93 which is anchored to the tie frame 23. The dash pot having risen with the lifter 75

bar 90, is free of the piston 93 when the lifter bar is released, and as it drops the piston 93 enters its bore thus cushioning the impact of the lifter bar.

Referring to Figs. 3 and 4, the tie frame 22 is provided with a transverse slot which, together with a recess in a cap 94 attached to the frame 22, guides the lifter bar 90. The bar 90 carries a head 95; attached to the ends of head 95 are brackets 96 which carry guide rods 97 sliding in bores in the lugs 98 of the tie frame 22. In transverse holes of the brackets 96 are adjustably mounted the pins 97a which are held therein by set screws (Fig. 4) and on which are supported blocks 98a. The channel 99 and angle 100 extending crosswise between the blocks 98a and brackets 96, respectively, form the platform for the articles. The vertical flange 101 of angle 100 serves as a side wall or stop for the articles. In lugs 98 of the frame 22 are supported a pair of cross rods 102 on which are adjustably mounted a pair of holders 103 in which are fixed the vertical guide rods 104. Holders 103 are clamped to one of the rods 102 by set screws, the rods 104 being placed so that they fit in the space between the channel 99 and angle 100.

An arm 105 attached to a stud 106 pivotally mounted in a bearing 107 of side frame 20, actuates a lever 108 fast on stud 106. The other end of lever 108 carries a stud 109 on which is pivotally mounted a bar 110. The end of bar 110 is provided with a latch 111 which is arranged to engage under the steps 112 and 113 of a notch in lifter bar 90. A spring 114 stretched between posts 115 and 116 of the bar 110 and tie frame 22 respectively, tends to hold the latch 111 against the notched side of the lifter bar 90. When the bar 90 is lifted it will readily be seen that the tension of the spring 114 will move the latch 111 into engagement with the steps 113 and 112.

Referring again to Fig. 2, when the hand-grip 34 is moved inwardly, the members assembled on the slide bars 28 and 29 travel along until the collars 117 mounted on bars 28 and 29 meet the bearing lugs 118 of brackets 26 and 27. Up to this time the compression of springs 119 on the rods 28 and 29, which are interposed between the slidably mounted U-bars 120 and adjustably mounted collars 121, has been great enough to keep pressed together on the bars 28 and 29 the members 31, 36 and 37 mounted thereon. The described movement of the bars 28 and 29 moves the cams 122 and 123 on one of the bars 120 past the roller 124, thus operating the arm 105 (Figs. 3 and 4). The upper cam 122 is adjustably attached while the lower cam 123 is fixedly attached to the bar 120, whereby the desired cam contour may be obtained by adjustment of the cam 122.

Referring to Fig. 5 the web feed mechanism consists of the pedestals 125 and 126 supporting cross shafts 127, 128 and 129 and the front pedestal 125 is provided with studs 131 and 132. The pedestals 125 and 126 are adjustably mounted on the bars 133 and 134 connecting the frames 20 and 21. A pair of studs 135 and 136 set in each of the pedestals 125 and 126 carry rollers resting on the top of the bars 133 and 134, and cross rods 137 connecting the pedestals bear against the bottom of bars 133 and 134. A handle 138 loosely mounted on stud 131 actuates an arm 139 loose on stud 131, the handle being provided with adjusting screws 161 bearing against a lug on the arm 139. The free end of arm 139 carries a stud 140 operating in the slotted head 141 of a

connecting rod 142 pinned to arm 144. The arm 144 is swingably mounted on stud 132 and carries a gear segment 145 meshing with a gear 146 on shaft 127, the latter being provided with a one-way ball clutch (not shown) which drives the gear 147 in a clockwise direction only. The gear 147 meshes with gear 148 fixed on shaft 128 thus turning a gear 149 fastened thereto, gear 149 meshing with a gear 150 on shaft 130. The shaft 128 also carries a feed roller 151 while the shaft 130 is equipped with a number of spaced rubber feed rollers 152 coating with roller 151 to feed the web of wrapping material. The shaft 130 is mounted in a swingable arm 153 pivoting on a shaft 154 mounted in the pedestals 125 and 126. At its other end arm 153 is equipped with a transverse lug 155 by means of which the same may be manually depressed thus lifting the feed rollers 152 out of engagement with the roller 151, this being only done when a new wrapper web is to be threaded between the feed rollers, or if the wrapper web should become jammed between the feed rollers. During normal operation the arm 153 is held securely to the shaft 154 by means of a set screw 156. As said feed rollers rotate they unwind the web W from a reel R of suitable wrapping material, such as waxed paper, etc., which is mounted on a shaft 157 (Fig. 1) supported on the bars 133, 134. The leading end of the wrapper web is guided over a bridge 158, and over the wires 159, which are held taut by weights 160, into position to be severed.

By means of the adjusting screws 161 handle 138 may be set at a convenient position for operation. When handle 138 is depressed, arm 139 actuates, through the rod 142 connecting the latter to the arm 144, the segment 145 which through the gear train 146-150 turns the feed rollers 151 and 152, thus advancing the wrapper web W a predetermined distance equal to the required length of material for wrapping the article. The arm 139 stops against an adjustable stop screw 161a threaded into a lug of frame 125, and the stop screw may be set to regulate the throw of said arm, in this manner providing means for regulating the length of the wrapper. When the handle 138 is returned to its neutral position as shown in Fig. 5 the arm 144 stops against a set screw 162.

When the wrapper is to be cut the handle 138 is first raised from its neutral position, thus bringing the adjusting screw 163 into engagement with the tail 164 of the arm 165 clamped to the pivot shaft 129 and causing an arm 166 on shaft 129 to raise and lift the knife bar 167 and knife 168 thereon. For this purpose the free end of arm 166 carries an adjusting screw 169 which engages the bar 167. The knife 168 when raised engages with a ledger plate 170 and severs the wrapper from the web W. During the cutting operation the stud 140 in arm 139 moves freely in the slot of head 141.

A portion of each of the bars 133 and 134 is provided with gear teeth 171 with which mesh the gear 172 mounted near the ends of cross shaft 173 journaled in pedestals 125, 126. The shaft 173 has a hand wheel 174 by which it can be turned to move the entire web feed unit for adjusting the distance between the knife 168 and the bight of the feed rollers when it is desired to change the length of the wrapper.

The operations by which the severed wrapper is folded about the loaf of bread or package will now be described. The severed wrapper is drawn over the cross bar 175 manually and positioned

so that it rests on the cross bar 175 and the plate 36. The loaves or packages A' to be wrapped are placed on the platform 176, Fig. 6 wherein they may be advanced by the attendant 5 until the leading loaf stops against the side wall 101. With the loaf thus positioned on the lifter platform 99-100, the lifter is raised by depressing the treadle 81, Fig. 1. The loaf A' on being raised to position A', Fig. 7, encounters the wrapper W and the same is thus draped about three 10 sides of the loaf. While the loaf is being raised to this position, the tuckers 44 encounter the top flaps of the wrapper and tuck the same down against the ends of the loaf. The stationary 15 rods 104 guide the loaf until it has entered between the tuckers 44. A tension plate 177 carried by rods slidably mounted in a bracket supported on the front cross bar 52 and rack 53 holds the wrapper W, Fig. 7, against the top of 20 the loaf, and remains in contact with the same until the bottom folds of the wrapper have been completed.

The lifter bar 90 upon being raised permits the 25 latch 111 of arm 110 to engage under the step 112 of the notch in bar 90, Fig. 4. In this position the bottom of the loaf A' is slightly higher than the bottom folder plate 37, Fig. 8, so that when the handle 34 is moved inward by the attendant the plate 37 may move under the loaf 30 and start to fold the hanging end of the wrapper under the bottom of the loaf. The continued advance of the plate 37 moves the cam 122-123 (Figs 2, 3 and 4) against the roller 124, thus moving the arm 105 which actuates the lever 35 108. The movement of lever 108 causes the arm 110 to release the latch 111 from its engagement with step 112, and the bar 90 drops until the latch 111 engages under the step 113.

Referring now to Fig. 9, the loaf A' is shown 40 in a tilted position supported by the end of plate 37 and the platform 100; the lifter 90 having dropped as described above, whereupon the plate 37 may be moved forward to complete its bottom fold as shown in Fig. 10. The loaf is now supported by the bottom folder 37, and as the further advance of the same moves the cam 122-123 (Figs. 2, 3 and 4) past the roller 124, the latch 111 in the manner heretofore described is withdrawn from under the step 113 allowing the 50 bar 90 to drop and return the platform 99-100 to its original position, Fig. 11. At this point the continued inward movement of the hand-grip 34 by the attendant brings the folders 40 into engagement with the side flaps of the wrapper and folds them over the top tuckers 44.

Referring once more to Fig. 2, the advance of 55 bottom folder 37 is stopped when the collars 117 mounted on the slide bars 28 and 29 meet the bearing lugs 118 of the brackets 26 and 27. The 60 collars 117 are so set that they will stop the advance of the plate 37 when it reaches a position slightly spaced from the bottom folder table 65 67, Fig. 11, and as the attendant continues pushing the handle 34 inward the force exerted on the 70 pusher 38 overcomes the tension of the springs 119, Fig. 2, thus sliding the pusher on the bars 28 and 29 and bringing it against the loaf and moving the cam rails 42 under the rollers 43, thereby causing the folders 44 to be swung up 75 above the now advancing loaf, Fig. 12. During the further advance of loaf A', Fig. 13, the skirt of the wrapper is folded under the bottom of the loaf by the front edge of the sealer table 67. The front side flaps of the wrapper are folded back against the previously folded flaps by the

5 folder plates 56a. The wrapped loaf A' at this point meets and pushes a package A'' which was left between the folders 56a from the previous operation. As the package A'' is thus forwarded its bottom flaps, which are still unfolded, 10 enter the slots 57 of the folder plates 56a and are gradually folded up against the ends of the package. A top tension plate 178 supported from the front cross bar 52 and rack 53 by a hinge holds the packages down on the sealer table 67 15 while they are forwarded between the folder plates 56a, sealer plates 60, and cooling plates 64, thus assuring a perfect bottom seal. It may be noted that the packages are advanced step by step between the sealing and cooling plates by 15 means of the packages subsequently pushed between the folder plates 56a, until the completely wrapped and sealed packages reach the delivery table 13. The finished package arriving on the delivery table 13 has the appearance shown in 20 Fig. 14.

What is claimed is:

1. In a hand operated wrapping machine, the combination with manually operable means for drawing a web of wrapping material from a roll 25 and severing a wrapper from the web, of devices for supporting the severed wrapper in a horizontal position, spaced swingable tuckers above said devices, a manually operable lifter arranged to move an article upwardly between said devices and tuckers to drape the wrapper about three sides of the article and tuck the wrapper down over the ends of the article, a manually operable horizontally movable slide, a bottom folder and a pair of spaced end folders on said slide adapted 30 when moved toward the article while said lifter is in an elevated position to fold one end of the wrapper under the bottom of the article and fold the forward side flaps of the wrapper over said tuckers, respectively, a heated sealer table 40 arranged to wipe the skirt of the wrapper under the bottom of the partially wrapped article when the latter is pushed thereover and heat seal the bottom seam so formed, spaced stationary folders on said table adapted to complete the folding of 45 the end flaps of the partially wrapped article when the latter is pushed therebetween, a pusher on said slide adapted to advance the partially wrapped article onto said table and between said stationary folders, spaced cam rails on said 50 pusher adapted to lift said tuckers up from the partially wrapped article, sealing plates beyond said stationary folders to heat seal the overlapped end flaps of the wrapper, and cooling plates beyond said sealing plates. 55

2. In a hand operated wrapping machine, the combination with manually operable means for drawing a web of wrapping material from a roll and severing a wrapper from the web, of devices for supporting the severed wrapper in a horizontal position, spaced swingable tuckers above said devices, a manually operable lifter arranged to move an article upwardly between said devices and tuckers to drape the wrapper about three sides of the article and tuck the wrapper down over the ends of the article, a manually operable horizontally movable slide, a bottom folder and a pair of spaced end folders on said slide adapted when moved toward the article while said lifter is in an elevated position to fold one end of the 65 wrapper under the bottom of the article and fold the forward side flaps of the wrapper over said tuckers, respectively, a heated sealer table arranged to wipe the skirt of the wrapper under the bottom of the partially wrapped article when 70 75

the latter is pushed thereover and heat seal the bottom seam so formed, spaced stationary folders on said table adapted to complete the folding of the end flaps of the partially wrapped article 5 when the latter is pushed therebetween, a pusher on said slide adapted to advance the partially wrapped article onto said table and between said stationary folders, spaced cam rails on said pusher adapted to lift said tuckers up from the 10 partially wrapped article, sealing plates beyond said stationary folders to heat seal the overlapped end flaps of the wrapper, cooling plates beyond said sealing plates, and a treadle connected to said lifter for raising the same.

15 3. In a hand operated wrapping machine, the combination with manually operable means for drawing a web of wrapping material from a roll and severing a wrapper from the web, of devices for supporting the severed wrapper in a horizontal position, spaced swingable tuckers above said devices, a manually operable lifter arranged to move an article upwardly between said devices and tuckers to drape the wrapper about three 20 sides of the article and tuck the wrapper down over the ends of the article, a manually operable horizontally movable slide, a bottom folder and a pair of spaced end folders on said slide adapted when moved toward the article while said lifter is in an elevated position to fold one end of the 25 wrapper under the bottom of the article and fold the forward side flaps of the wrapper over said tuckers, respectively, a heated sealer table arranged to wipe the skirt of the wrapper under the bottom of the partially wrapped article when the latter is pushed thereover and heat seal the bottom seam so formed, spaced stationary folders adapted to complete the folding of the end flaps of the partially wrapped article 30 when the latter is pushed therebetween, a pusher on said slide adapted to advance the partially wrapped article onto said table and between said stationary folders, and spaced cam rails on said pusher adapted to lift said tuckers up from the 35 partially wrapped article, said slide including a pair of connected slide bars on which said bottom folder is loosely mounted and said pusher is loosely mounted behind said bottom folder, a hand-grip mounted on said pusher, the end folders also being mounted on the pusher, stationary bearing lugs in which said bars are 40 slidably mounted, collars fixed on said bars, and springs seated against said collars and pressing said pusher against said bottom folder, whereby forward movement of said hand grip will move the bottom folder in unison with the pusher until 45 said collars engage said lugs.

40 4. The combination with devices for supporting a wrapper in a horizontal position, of spaced swingable tuckers above said devices, a lifter arranged to move an article upwardly between said devices and tuckers to drape the wrapper about the article and tuck the wrapper down over the ends of the article, a horizontally movable slide, a bottom folder and a pair of spaced end folders 45 on said slide adapted when moved toward the article while said lifter is in an elevated position to fold one end of the wrapper under the bottom of the article and fold the forward side flaps of the 50 wrapper over said tuckers, respectively, and spaced cam rails carried by said slide and adapted to lift said tuckers up from the partially wrapped article.

55 5. The combination with devices for supporting a wrapper in a horizontal position, of spaced swingable tuckers above said devices, a lifter arranged to move an article upwardly between said devices and tuckers to drape the wrapper about the article and tuck the wrapper down over the ends of the article, a horizontally movable slide, a bottom folder and a pair of spaced end folders 60 on said slide adapted when moved toward the article while said lifter is in an elevated position to fold one end of the wrapper under the bottom of the article and fold the forward side flaps of the wrapper over said tuckers, respectively, a heated sealer table arranged to wipe the skirt of the 65 wrapper under the bottom of the partially wrapped article when the latter is pushed thereover and heat seal the bottom seam so formed, spaced stationary folders adapted to complete the folding of the end flaps of the partially wrapped 70 article.

75 6. The combination with devices for supporting a wrapper in a horizontal position, of spaced swingable tuckers above said devices, a lifter arranged to move an article upwardly between said devices and tuckers to drape the wrapper about the article when the latter is pushed therebetween, a pusher on said slide adapted to advance the partially wrapped article onto said table and between said stationary folders, and spaced cam rails on said pusher adapted to lift said tuckers up from the partially wrapped article.

8. The combination with devices for supporting a wrapper in a horizontal position, of spaced swingable tuckers above said devices, a lifter arranged to move an article upwardly between said devices and tuckers to drape the wrapper about the article and tuck the wrapper down over the ends of the article, a horizontally movable slide, a bottom folder and a pair of spaced end folders on said slide adapted when moved toward the article while said lifter is in an elevated position to fold one end of the wrapper under the bottom of the article and fold the forward side flaps of the wrapper over said tuckers, respectively, a heated sealer table arranged to wipe the skirt of the wrapper under the bottom of the partially wrapped article when the latter is pushed thereover and heat seal the bottom seam so formed, spaced stationary folders adapted to complete the folding of the end flaps of the partially wrapped article when the latter is pushed therebetween, a pusher on said slide adapted to advance the partially wrapped article onto said table and between said stationary folders, and spaced cam rails on said pusher adapted to lift said tuckers up from the partially wrapped article, said slide including a pair of connected slide bars on which said bottom folder is loosely mounted and said pusher is loosely mounted behind said bottom folder, a hand-grip mounted on said pusher, the end folders also being mounted on the pusher, stationary bearing lugs in which said bars are slidably mounted, collars fixed on said bars, and springs seated against said collars and pressing said pusher against said bottom folder, whereby forward movement of said hand grip will move the bottom folder in unison with the pusher until said collars engage said lugs.

9. The combination with devices for supporting a wrapper in a horizontal position, of spaced swingable tuckers above said devices, a lifter arranged to move an article upwardly between said devices and tuckers to drape the wrapper about the article and tuck the wrapper down over the ends of the article, a horizontally movable slide, a bottom folder and a pair of spaced end folders on said slide adapted when moved toward the article while said lifter is in an elevated position to fold one end of the wrapper under the bottom of the article and fold the forward side flaps of the 65 wrapper over said tuckers, respectively, and spaced cam rails carried by said slide and adapted to lift said tuckers up from the partially wrapped article.

10. The combination with devices for supporting a wrapper in a horizontal position, of spaced swingable tuckers above said devices, a lifter arranged to move an article upwardly between said devices and tuckers to drape the wrapper about the article and tuck the wrapper down over the ends of the article, a horizontally movable slide, spaced end folders on said slide adapted when moved toward the article while said lifter is in an elevated position to fold the forward side flaps of the wrapper over said tuckers, and spaced cam rails carried by said slide and adapted to lift said tuckers up from the partially wrapped article.

11. A wrapping machine having the features claimed in claim 19 in which a latch is provided

for retaining said lifter in an elevated position, and a pusher for moving the article off said lifter while the latter is latched in an elevated position.

9. A wrapping machine having the features 5 claimed in claim 19, in which a latch is provided for retaining said lifter in an elevated position, a yielding tension plate arranged to engage the article while it is being raised and hold it down on said lifter, and a pusher for moving the article off said lifter while the latter is latched in an elevated position.

10. A wrapping machine having the features 10 claimed in claim 19, in which a yielding tension plate is provided to hold the wrapper against the 15 top of the article, and a pusher for moving the partially wrapped article off said lifter while the latter is latched in an elevated position.

11. The combination with a lifter arranged to 20 raise an article, of a latch for retaining said lifter in an elevated position, a horizontally movable slide, a pusher on said slide adapted to push the article off said lifter, a cam on said slide, and means controlled by said cam for disengaging said 25 latch from said lifter.

12. The combination with a lifter arranged to 30 raise an article, of a latch for retaining said lifter in an elevated position, a horizontally movable slide, a pusher on said slide adapted to push the article off said lifter, a cam on said slide, and means controlled by said cam for disengaging 35 said latch from said lifter, said lifter including a vertically reciprocable lifter bar having a notched edge, and said means including an arm connected to said latch, a roller on said arm disposed in the path of said cam so that said arm will be actuated thereby to move said latch out of said notch, and a spring urging said latch against said lifter bar so that it will enter said notch when said lifter bar is raised.

13. The combination with devices for supporting 40 a wrapper in a horizontal position, of a lifter arranged to raise an article between said devices to drape the wrapper about the article, a horizontally movable slide, a latch for retaining said lifter in an elevated position, a bottom folder and a pusher on said slide adapted to fold one end of the wrapper under the bottom of the article and move the partially wrapped article off said lifter while the latter is latched in an elevated position, 45 a cam on said slide, and means actuated by said cam for disengaging said latch from said lifter.

14. The combination with devices for supporting 50 a wrapper in a horizontal position, of a lifter arranged to raise an article between said devices to drape the wrapper about the article, a horizontally movable slide, a latch for retaining said lifter in an elevated position, a bottom folder and a pusher on said slide adapted to fold one end of the wrapper under the bottom of the article 55 and move the partially wrapped article off said lifter while the latter is latched in an elevated position, a cam on said slide, and means actuated by said cam for disengaging said latch from said lifter, said lifter including a lifter bar having a notched edge, the notch having two steps at different levels, and said means including a spring connected to said latch and urging it against said lifter bar so that it will engage under the lower step when the lifter bar is raised, and said means 60 including an arm connected to said latch, and a roller on said arm disposed in the path of said cam, whereby said latch will be withdrawn from under the lower step and engaged under the upper step when said roller encounters said cam 65 during the advance of said slide to permit said

75 folder to fold the wrapper end under the bottom of the article, and said latch will be withdrawn from the notch as the cam is moved past the roller so that the partially wrapped article will be supported by said bottom folder and said lifter 5 may return to its lower position.

15. A wrapping machine of the class described 10 having a vertically movable lifter bar, a head on said bar adapted to support an article, devices above said head for supporting a wrapper in a horizontal position, and further characterized by having spaced top tuckers above said devices, whereby the wrapper will be draped about the article and tucked down over the ends of the article when it is raised between said devices and 15 tuckers on said head, and stationary rods engaging the ends of the loaf for guiding the same while it is being raised, until it enters between said tuckers.

16. In an exclusively manually operable wrap- 20 ping machine of the class described: the combination with a pair of slide bars, of a cross bar fast to said slide bars, a bottom folder loosely mounted on said slide bars behind said cross bar, a pusher loosely mounted on said slide bars behind said 25 bottom folder, a hand-grip mounted on said pusher, a pair of stationary bearing lugs in which said slide bars are slidably mounted, collars fixed on said bars, and springs seated against said 30 collars and pressing said pusher, folder and cross bar together, whereby forward movement of said hand-grip will move the bottom folder in unison with the pusher until the collars engage the bearing lugs.

17. In an exclusively manually operable wrap- 35 ping machine of the class described: the combination with a pair of slide bars, of a cross bar fast to said slide bars, a bottom folder loosely mounted on said slide bars behind said cross bar, a pusher loosely mounted on said slide bars behind said 40 bottom folder, a pair of stationary bearing lugs in which said slide bars are slidably mounted, spaced end folders mounted on said pusher, collars fixed on said slide bars, and springs seated against said collars and pressing said pusher, folder and cross 45 bar together, whereby forward movement of the pusher will move the bottom folder in unison with the pusher until the collars engage the bearing lugs.

18. A wrapping machine having the features 50 claimed in claim 19, in which a pivoted tucker, made effective by manual advancement of the article feeding mechanism to tuck a wrapper down over the end of said article, is thereafter 55 lifted by a cam rail by virtue of further manual advancement of said article.

19. A wrapping machine of the class described: 60 comprising in combination a support for a supply roll of wrapping material in web form; means operable manually at will to withdraw and sever therefrom a wrapping sheet and to position said sheet at a station provided with wrapping devices; a lifter adapted to receive an article to be wrapped and operable manually at will to advance said article upward into said wrapping station, thereby draping said article with the sheet; and means to transfer said draped article manually at will from said wrapping station to a 65 station provided with sealing devices; and means actuated during, and by virtue of, said transfer to effect a further wrapping operation upon said sheet.

20. A wrapping machine of the class described: 70 comprising in combination a support for a supply 75

roll of wrapping material in web form; means operable manually at will to withdraw and sever therefrom a wrapping sheet and to position said sheet at a station provided with wrapping devices; a lifter adapted to receive an article to be wrapped and operable manually at will to advance said article upward into said wrapping station, thereby draping said article with the sheet, and causing said wrapping devices to become effective; means to transfer said draped article manually at will from said wrapping sta-

tion to a station provided with sealing devices; means actuated during, and by virtue of, said transfer, to effect a further wrapping operation upon said sheet and to make said sealing devices effective; said means co-operating to discharge said wrapped, sealed article from said sealing station.
